UNITED STATES PATENT OFFICE.

ERNST W. JOHNSON, OF NEW YORK, N. Y.

SHOE-POLISHING MACHINE.

1,059,369.

Specification of Letters Patent. Patented Apr. 22, 1913.

Application filed March 14, 1912. Serial No. 683,685.

To all whom it may concern:

Be it known that I, ERNST W. JOHNSON, a citizen of the United States, and residing at New York, in the county of New York and State of New York, have invented certain new and useful Improvements in Shoe-Polishing Machines, of which the following is a specification, such as will enable those skilled in the art to which it appertains to make and use the same.

This invention relates to machines for polishing shoes, and the object thereof is to provide an improved machine of this class which is automatic in operation and which is set for operation by the insertion of a coin and which is set in operation by placing the foot on a suitable support and forcing said support downwardly, which operation sprays the shoe with liquid blacking and then puts in motion the polishing brushes with which the machine is provided, and the construction and operation being such that when the brushes, having completed their work of polishing the shoe the operation of the machine is automatically stopped, by breaking the circuit of an electric motor by which the machine is operated, and at which time the foot is removed from the support and the operative parts returned to their normal position and automatically locked.

The invention is fully disclosed in the following specification of which the accompanying drawings form a part, in which the separate parts of my invention are designated by suitable reference characters in each of the views, and in which:

Figure 1 is a longitudinal vertical section of my machine on the line 1—1 of Fig. 2; Fig. 2 a transverse vertical section on the line 2—2 of Fig. 3; Fig. 3 a plan view of the bottom part of the machine with the casing removed and parts broken away; Fig. 4 a side view of the machine on a reduced scale and with parts of the construction broken away; Fig. 5 a central vertical section through the top part of the machine and showing the parts in inoperative position; and Fig. 6 a view similar to Fig. 5 but shewing the parts in an operative position.

1, designates a casing which houses the entire mechanism and is composed of a vertical top part 2, and a horizontal base 3. The top part 2 comprises a front wall 4,

and a removable back 5, and is closed at the top and sides, as shown.

The front wall 4 is provided with an opening 6, which enters into a coin receptacle 7, and is closed by a door 8, having a suitable lock 9, and above the opening 6, I provide a coin support 10, which forms one side of a slot 11, and passing through the front wall 4 of the top 2 of the casing 1, and slidably mounted in the slot 11 is a plunger bar 12, having a thumb piece 13, at its outer end and provided with a circular coin aperture 14, about central of its length which is adapted to receive a coin 15, when the machine is to be operated, as will hereinafter appear. The plunger bar 12, is further provided, near its inner end with spaced perforated lugs 16, between which is pivoted a link 17 which is pivotally connected at its rear end with a switch arm 18, of a bell crank lever 19, mounted as shown at 20, in the top 2 of the casing 1, and having a short arm 21, to which is connected a wire or cable 22, as shown.

In order to prevent unscrupulous persons from operating the machine without depositing the necessary coin in the aperture 14, I provide a stop dog 23, pivoted at 24, immediately above the plunger bar 12, and which is provided with a forwardly and downwardly directed nose 25, which is tensionally held in contact with the plunger bar 12, and will enter the coin aperture 14, as it passes underneath, if there is no coin therein, and stop the inward movement of the plunger bar 12. If, however, the necessary coin is deposited in the aperture 14, the nose 25 of the dog 23, will ride over it, as the plunger bar 12, is of the same thickness as the coin, as shown in Fig. 5, and the dog 23, is provided with a tail piece 26, connected with one end of a pull spring 27, the other end being anchored to the casing at 28.

Pivoted at 29, in the casing is a trip lever 30, having a downwardly directed arm 31, ranging across the path of movement of the plunger bar 12, and a backwardly directed arm 32, having a trip wire or cable 33, connected therewith, and which is adapted to rest on a stop pin 34, when the mechanism is in its inoperative position and locked as will be hereinafter explained.

The trip lever 30, is so placed that, if

there is no coin placed in the aperture 14, and the plunger bar 12, is forced inwardly, the nose 25 of the dog 23, will stop the inward movement of said plunger bar 12 before the rear end thereof contacts with the downwardly directed arm 31.

The switch arm 18 of the bell crank lever 19 is adapted, when the parts are in the operative position as shown in Fig. 6, to make electrical connection between two contacts 35, which form the terminals of a motor circuit 36.

Secured to the back 5, of the casing is a bracket 37, having a grooved wheel 38, mounted therein and around and over which is passed a chain 39, one end of which is provided with a weight 40, the other end being carried down to and around a grooved wheel 41, mounted at 42, and then forwardly to and around another grooved wheel 43, mounted at 44, to a stationary table 45, and then downwardly to an eye or staple 46, fixed on a vertically movable bar 47.

The stationary table 45, is supported within the base 3, of the casing 1, by standards 48, which are bolted to the table 45, and to the bottom 49 of the base 3, as shown and these standards 48, are provided with integral keepers 50, in which are movable lock bolts 51, having reduced extensions 52, passing through cap pieces 53, between which and the bolts 51, are placed push springs 54, which normally tend to force the bolts 51, against bars 55, vertically movable in central bores 56, in the standards 48, and these bars 55, are connected at the upper ends thereof with a foot rest 57, which when the parts are in the normal inoperative position assumes the elevated position shown in dotted lines in Fig. 1, and when in this position the bars 55, and foot rest 57 are held against downward movement by the lock bolts 51, projecting into the bores 56, and under the lower ends of the bars 55, as will be readily understood.

Connected with the reduced extensions 52 of the bolts 51 are wires or cables 58, which are passed around grooved wheels 59, carried in a bracket 60, secured to the stationary table 45, and these wires or cables 58, are brought together at 61, and connected to the trip wire or cable 33 which is passed around a grooved wheel 62, mounted in the base 63, of the casing, as shown.

The standards 48 are further provided with longitudinal slots 63, through which project perforated pins 64, to which are connected wires or cables 65 and 66, which are passed under and around grooved wheels 67 and 68, and the wire or cable 65 is connected to the downwardly directed arm 69, of a bell crank lever 70, which is pivoted at 71, in the base 3 of the casing.

The shorter arm 72, of the crank lever 70, has connected thereto a wire or cable 73

which passes over and around a grooved wheel 74 rotatably mounted in the base 3 and then backwardly and is connected to a grooved wheel 75, around which passes a wire or cable 76, both ends of which are connected as at 77, to a brush strap 78, provided with long bristles 79, as shown.

The wire or cable 66, at the opposite end of the foot rest from the wire or cable 65, is passed upwardly and around a grooved wheel 80, rotatably mounted in the base 3, and then backwardly and is connected to the lower end 81, of a lever arm 82, loosely mounted at 83, in a bracket 84, secured to the back 5, of the base 3 of the casing 1.

The lever arm 82, is extended above the bracket 84, and is connected at 85, with a wire or cable 86, to which is secured a grooved wheel 87, around which is passed a wire or cable 88, both ends of which are secured as at 89, to a brush strap 90, having long bristles 91, as shown, and the brush straps 78 and 90 are U-shaped in form and are positioned so that the open sides are adjacent and this construction forms an elliptical band brush which surrounds the shoe when in operation, and when given a quick circular reciprocatory movement, thoroughly brushes the shoe as will be readily understood.

The adjacent ends of the U-shaped brush straps 78 and 90 are provided with perforated angle plates 92 between which are placed cross-heads 93, having longitudinal reduced extensions 94, passing loosely through the angle plates 92, and provided with nuts 95, between which and the angle plates 92, are placed spiral springs 96, which are carried on the extensions 94, as shown, and the cross-heads 93 are connected by integral right angle extensions 97, to blocks 98, slidably mounted on horizontal bars 99, mounted in fixed standards 100, secured to the table 45.

The sliding blocks 98, have short pins 110, on which are pivotally mounted one end of pitman rods 102 and 103 the opposite ends of said pitman rods being carried on wrist pins 104 and 105 which are carried respectively on a gear wheel 106, and a balance wheel 107, fixed to the opposite ends of a rotatable shaft 108, mounted in suitable standard bearings 109 and 110, and the wrist pins 104 and 105 are arranged opposite of each other as indicated on dotted lines in Fig. 1, so that when one of the sliding blocks reaches its outward limit of movement the opposite block has just reached its inward limit of movement, and this construction gives the band brush at opposite sides an opposite reciprocatory movement similar to that used by boot blacks in polishing shoes.

The standard bearing 110, is provided with a supplemental bearing 111, extending upwardly and slightly backwardly and car-

ries a rotatable shaft 112, having fixed thereto a disk 113, provided, in the form of construction shown, with ten pins 114, which are adapted to be struck successively by a trip pin 115, carried by the gear wheel 106, and a cam disk 116, is also fixed to the shaft 112, and is provided with a cam face 117, adapted to co-act with a beveled nose 118, of a lever arm 119, pivotally mounted at 120, in the supplemental bearing 111. The forward end of the lever arm 119, is connected to the lower end of the wire or cable 22, and, when the parts are in the operative position shown in Figs. 1 and 6, and after 15 the shaft 108, has made a predetermined number of revolutions, determined by the number of pins in the disk 113, in this case it being ten, the came face 117, will operate the lever arm 119, to exert a pull on the 20 wire or cable 22, which will throw the switch arm 18, away from the contacts 35, and break the motor circuit to stop the mechanism.

The motor circuit 36, comprises, in addition to the contacts 35 and switch arm 18, a battery 121, and a mechanically operated blade switch 122, secured in the base 3 of the casing, which comprises a standard 123, an insulating block 124, having spring 30 blades 125 and 126, secured thereto, one of which, the blade 125, being backed up by a set screw 127, the blade 126 being in the path of a spring pressed plunger 128, having an enlarged head 129, movable in a suitable 35 keeper, as at 130, and one end of which is provided with a beveled face 131, against which the lower end of the vertically movable bar 55, impinges to force the head 129, and a plunger 128 backwardly against the 40 spring blade 126, to cause it to contact with the blade 125 to close the motor circuit.

The motor terminals are shown at 132 and 133, and a conductor 134 is connected to the terminal 133, and with the switch blade 126, 45 another conductor 135, is connected to the switch blade 125, and through the battery to one of the contacts 35, and another conductor 136, is connected to the other of the contacts 35 and with the motor terminal 132.

50 In order to give a high polish to the top of the toe part of the shoe, I provide a swinging brush 137, which operates in a horizontal plane over the front of the shoe and swings upwardly and backwardly, out 55 of sight, when not in use. Mounted on the extreme rear end of the table 45, is a standard 138, having a socket 139 in its top to receive a pivot pin 140, which is provided with an annular groove 141, adapted to receive 60 the end of a retaining screw 142. The pivot pin is carried by a forked block 143, through which is passed a shaft 144, on which is mounted, in the forked block 143, the reduced shank 145, of the brush 137, which is 65 provided with a tail piece 146, to limit its

upward and backward movement, as will be readily understood.

The lever arm 82, is provided with an angular extension 147, and connected therewith is a wire or cable 148, passing over and around a grooved wheel 149, mounted in the base 3 of the casing; and is then connected with the shank 145, of the brush 137 at 150.

The motor is shown at 151, the motor shaft at 152, and the power gear at 153, which is meshed with the gear 106, and drives the machine when in operation.

The foregoing all pertains to the control and operation of the polishing mechanism and I will now describe the automatic pneumatic means for spraying the shoe with liquid blacking as it enters the base 3 of the casing and before the polishing means is set in operation.

The base 3 of the casing is provided with an opening 154, through which the foot rest 57, normally protrudes slightly, it being normally held elevated as indicated by the dotted lines in Fig. 1 and full lines in Fig. 4, by the weight 40, as will be readily understood.

When it is desired to get a shine, a coin is placed in the aperture 14, and the plunger bar 12, forced inwardly, this operation throws the parts into the position shown in Fig. 6, and causes a pull to be exerted on the wires or cables 22 and 33, and this closes the motor circuit through the switch arm 18. The pull on the wire or cable 22, throws the beveled nose 118, down in the path of the cam face 117, while the pull on the wire or cable 33, withdraws the lock-bolts 51, from under the lower ends of the bars 55. The foot is now placed on the foot rest 57, and sufficient pressure is placed on the foot to 100 depress the foot rest against the action of the weight 40. As the foot rest descends, air is forced through flexible tubes 155, through the instrumentality of piston rods 156, pistons 157, and cylinders 158; the piston rods 156, being secured to the descending foot rest 57, while the cylinders 158, are secured to the table 45. The cylinders are provided just below the upward limit of movement of the pistons 157, with air inlets 115 159, which are closed just as soon as the pistons start downward.

The cylinders are provided near the lower ends thereof with air outlets 160, and the tubes 155 are connected with these outlets 120 as at 161 and said tubes 155, are connected at or near the top of the base 3 of the casing, with horizontally movable metallic pipes 162, passing through suitable keepers 163, and connected with blacking spray-pipes 164, of semi-elliptic form and provided with small perforations 165, in the inner walls thereof and these perforations are carried around the rear end of the sprays so that the front as well as the sides of the shoe 130

can be thoroughly covered with liquid blacking.

The air pipes 162, are tapped at 166, for the attachment of liquid blacking pipes 167, to which are secured flexible tubes 168, which convey the liquid blacking from the blacking tanks 169, to the spray-pipes 164.

In order to separate the spray-pipes 164, after the shoe is polished to permit the foot 10 to be withdrawn, I provide slidable bars 170, mounted in keepers 171, and having reduced slidable extensions 172, slidable in keepers 173, between which and the bars 170, are placed springs 174, as shown, and stop pins 15 175, are provided to limit the inward movement of the spray-pipes 164.

It will be understood that all of the keepers 163—171, and 173 are secured to the underside of the top of the base 3 of the casing.

20 Secured to the reduced extensions 172, are wires or cables 176, which are carried outwardly over and around grooved wheels 177, and then downwardly and connected with outwardly directed arms 178, of bell crank 25 levers 179, pivoted at 180, in brackets 181, secured to the side walls of the base 3 of the casing, and wires or cables 182 are secured at 183, to the vertically movable bar 47, and are passed under and around grooved wheels 30 184, and then outwardly and secured to downwardly directed arms 185 of the bell crank lever 179, as shown.

In order to impart to the brush 137 a horizontal swinging reciprocatory movement 35 over the toe portion of the shoe, I provide the shaft 144 with slotted extensions 186, which are adapted to receive pins 187 carried by horizontally movable forked bars 188, slidable in suitable keepers 189, secured 40 to the two rear fixed standards 100, and the rear ends of the block 98 are provided with lateral shoulders 190, which are adapted to strike the front ends of the opposite bars 188 alternately to oscillate the bar 144, on its 45 pivot pin 140, and give the brush a swinging reciprocatory movement as hereinbefore stated.

When the machine is at rest or when the parts are in the inoperative position, the 50 lock bolts 51, range across the bores 56, and underlies the lower ends of the bars 55, and lock the foot rest 57, against downward movement, but when a coin is inserted in the recess 14, and the plunger bar 12, pushed inwardly it strikes the arm 31, of the lever 30, and rocks the same which creates an upward pull on the trip wire or cable 33 and this 55 operation withdraws the lock bolts 51, from the bores 56, after which the foot may be 60 placed on the foot rest 57, and pressed downwardly, and as the foot rest and its associated parts descend, the wires or cables 65, 66 and 182 are drawn outward over the grooved wheels 67, 68 and 184 by the action 65 of the springs 94 and 174, which operation

forces the brush straps 78 and 90 and the spray-pipes 164, inwardly in close relation to the shoe to be polished. The downward movement of the foot rest 57, also acts to release the pull on the wire or cable 148, and this permits the brush 137, to drop down over the toe of the shoe and just before the foot rest reaches its downward limit of movement and after the shoe has been sprayed with liquid blacking, the lower end of the rear bar 55, strikes the cam face 131, of the plunger 128, and forces said plunger backwardly to close the switch 122, and starts the motor which operates the brushes to polish the shoe, and as hereinbefore stated after a predetermined number of movements of the polishing brushes, the motor circuit is automatically broken by the cam face 117, operating the lever 119 to exert a downward pull on the wire or cable 22 which throws the switch arm 18, out of engagement with the contacts 35 as will be readily understood. It will also be understood that the weight 40, acts to elevate the foot rest 57, which operation separates the brush straps 78 and 90, as indicated by dotted lines in Fig. 5, and also separates the spray-pipes 164, after the machine comes to a stop and as the foot is being withdrawn from the machine.

I do not desire to be understood as limiting myself to the detail features and construction and arrangement of parts as herein shown and described, as it is manifest that variations and modifications therein may be resorted to, in the adaption of my invention to varying conditions of use without departing from the spirit and scope of my invention and improvements. I therefore reserve the right to all such variations and modifications as properly fall within the scope of my invention and the terms of the following claims.

Having fully described my invention what I claim as new and desire to secure by Letters Patent is:—

1. In a shoe polishing machine, the combination with a band brush adapted to encircle a shoe and consisting of two sections resiliently connected and held together, of an adjustable foot-rest and means for separating the sections of the band brush upon the elevation of the foot-rest.

2. In a shoe polishing machine, the combination of a vertically movable foot-rest, oppositely disposed spray pipes, a band brush adapted to encircle a shoe and consisting of movably connected sections, a brush adapted to operate on the toe of a shoe, means adapted to separate the sections of the band brush, to separate the spray pipes and to elevate the toe brush.

3. In a shoe polishing machine the combination with an adjustable foot-rest of spray pipes resiliently pressed toward the

shoe, means for withdrawing the spray pipes from the shoe on the elevation of the foot-rest and means operated by the depression of the foot-rest to force polishing material 5 through the spray pipes.

4. In a shoe polishing machine, a band brush adapted to encircle a shoe and consisting of two sections resiliently connected, an adjustable foot-rest, means for separating 10 the sections of the band brush upon the elevation of the foot-rest, a toe brush and means for giving the band brush a reciprocatory movement and for giving the toe brush a longitudinal oscillatory movement.
- 15 5. In a shoe polishing machine, a band brush adapted to encircle a shoe and consisting of two sections resiliently connected, an adjustable foot-rest, means for separating the sections of the band brush upon the elevation of the foot-rest, a toe brush and means for giving the band brush a reciprocatory movement and for giving the toe brush a longitudinal oscillatory movement, said 20 means consisting of oppositely reciprocating

ing sliding blocks connected with the band brush at the sides thereof and having a pitman crank connection with a motor driven shaft, and sliding bars adapted to be alternately struck by said sliding blocks to operate a transverse oscillating bar.

6. The combination of an adjustable foot-rest, oppositely disposed spray pipes adapted to encircle the shoe, a band brush adapted to encircle the shoe and consisting of two sections, and a brush adapted to operate on the toe of a shoe with means adapted on elevation of the foot-rest, to separate the sections of the band brush, to separate the spray pipes and to elevate the toe brush.

In testimony that I claim the foregoing as my invention I have signed my name in presence of the subscribing witnesses this 12th day of March, 1912.

ERNST W. JOHNSON.
